LATCH FOR LUGGAGE AND LIKE CASES

John B. Humphries, Stamford, Conn., assignor to The
Excelsior Hardware Company, Stamford, Conn.

Filed Feb. 18, 1963, Ser. No. 73,622

Term of patent 14 years

(Cl. D50—7)

FIGURE 1 is a perspective view of a latch for luggage and like cases showing my new design;

FIGURE 2 is a view showing one side of the latch of FIGURE 1, the opposite side is substantially the same;

FIGURE 3 is a front view thereof. The rear not shown is substantially plain;

FIGURE 4 is an end view thereof viewed from the left of FIGURE 3; and

FIGURE 5 is an end view thereof viewed from the right of FIGURE 3.

The members protruding in back of the latch and seen in FIGURES 2, 4 and 5 suitably have circular cross-sections.

The dominant features of the design reside in the solid line portions of the figures.

I claim:

The ornamental design for a latch for luggage and like cases, substantially as shown and described.
